US00D945698S

(12) **United States Design Patent** (10) Patent No.: **US D945,698 S**
(45) Date of Patent: **** Mar. 8, 2022**

(54) **INHALER**

(71) Applicant: **PNEUMA RESPIRATORY, INC.**,
Boone, NC (US)

(72) Inventors: **Jay Morgan**, Knoxville, TN (US);
Charles Eric Hunter, Boone, NC (US);
Scott Buchanan, Knoxville, TN (US);
Mark McComas, Knoxville, TN (US);
Justin Couch, Knoxville, TN (US)

(**) Term: **15 Years**

(21) Appl. No.: **29/717,211**

(22) Filed: **Dec. 16, 2019**

Related U.S. Application Data

(63) Continuation of application No. 29/707,248, filed on
Sep. 26, 2019.

CLAIM

The ornamental design for an inhaler, as shown and
described.

DESCRIPTION

FIG. 1 is an isometric view of an inhaler showing our new
design.

FIG. 2 is a bottom perspective view thereof.

FIG. 3 is a front view thereof.

FIG. 4 is a back view thereof.

FIG. 5 is a left side view thereof.

FIG. 6 is a right side view thereof.

FIG. 7 is a top view thereof; and,

FIG. 8 is a bottom view thereof.

The broken lines shown in the Figures depict portions of the
inhaler that form no part of the claimed design.

1 Claim, 7 Drawing Sheets
